(57) **CLAIM**

The ornamental design for a toilet brush and holder set as shown and described.

DESCRIPTION

FIG. 1 is a front perspective view of a holder of a toilet brush and holder set showing our new design;

FIG. 2 is a bottom perspective view thereof;

FIG. 3 is a top perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof;

FIG. 10 is a perspective view of a brush of the toilet brush and holder set showing our new design;

FIG. 11 is another perspective view thereof;

FIG. 12 is a front view thereof;

FIG. 13 is a rear view thereof;

FIG. 14 is a left side view thereof;

FIG. 15 is a right side view thereof;

FIG. 16 is a top view thereof;

FIG. 17 is a bottom view thereof;

FIG. 18 is an enlarged view of portion 18 shown in FIG. 10;

FIG. 19 is a perspective view of the toilet brush and holder set;

FIG. 20 is another perspective view thereof;

FIG. 21 is a front view thereof;

FIG. 22 is a rear view thereof;

FIG. 23 is a left side view thereof;

FIG. 24 is a right side view thereof;

FIG. 25 is a top view thereof;

FIG. 26 is a bottom view thereof;

FIG. 27 is an enlarged view of portion 27 shown in FIG. 19; and,

FIG. 28 is an exploded perspective view of the toilet brush and holder set.

The dash-dash broken lines in the drawings depict portions of the toilet brush and holder set that form no part of the claimed design.

The dot-dash broken lines represent boundaries of the enlarged portions and form no part of the claimed design.

1 Claim, 28 Drawing Sheets
